UNITED STATES PATENT OFFICE.

EDGAR M. CLARK, OF NEW YORK, N. Y., AND FRANK A. HOWARD, OF ELIZABETH, NEW JERSEY, ASSIGNORS TO STANDARD OIL DEVELOPMENT COMPANY, A CORPORATION OF DELAWARE.

ART OF DISTILLING OILS.

Application filed December 24, 1920. Serial No. 432,897.

The present invention relates to the distillation of hydrocarbon oils, and more particularly to the pressure distillation of such oils of higher boiling point for their pyro-
5 genetic conversion into lower boiling point oils. It will be fully understood from the following description of a specific embodiment thereof, which is illustrated by the accompanying drawings, in which:

10 Fig. 1 is an elevation, partially in section, of a still suitable for carrying out the present invention and its associated dephlegmating apparatus; and

15 Fig. 2 is a broken plan view of a battery of stills such as is shown in Fig. 1.

Referring more particularly to the drawings, the numeral 5 indicates a bulk supply container for the oil being distilled, this container having suitably the form of a horizontal cylindrical drum or shell. This drum is mounted upon a suitable furnace setting 6, and the pipes or legs 7 and 8 depend vertically from point near its ends. The legs 7 and 8 communicate with headers 9 and 20 10, respectively, and as the leg 7 is longer than the leg 8, the header 9 is lower in position than the header 10. Rows or banks of upwardly inclined tubes 11, 11 connect the headers 9 and 10, these tubes being exposed 25 to the direct heat of the combustion gases of the furnace. A deck 12 over the tubes protects the drum 5 from the direct heat of the furnace. The drum 5 is provided with the usual manholes, liquid level and pressure 30 gages.

35 The vapors evolved in drum 5 pass out through the vapor pipe 13 into the vapor space 14 provided in a drum 15 near one end of the latter. The drum 15, which is suitably of approximately the same size as the drum 5, may be of the horizontal cylindrical type, and may be supported upon the drum 5 at one end by the vapor pipe 13 and at the other by a roller 16 which rests upon the drum 5 and with which the drum 15 has a rolling contact. The drum 15, which is of the type of liquid condenser more fully described in the patent of one of us, No. 1,405,286 granted, January 31st, 1922, is provided with a vertical partition 17 which divides it into a gas or vapor space 14, and a liquid chamber 18. A dam 19 extends transversely across the vapor space between the partition 17 and the opening of the vapor

55 pipe 13 into said vapor space. This dam 19 extends up to within a short distance of the top of the drum 15. An overflow pipe 20, which passes through the partition 17 and opens into the liquid space 18, passes thru the vapor space 14 and downwardly thru the 60 vapor pipe 13 into the drum 5, where it opens slightly above the top of the leg 7 which communicates with the lower header 9. A low dam 21 extends across the drum 5 in front of the opening of the leg 7, thereby causing the reflux and the feed stock which enters thru the pipe 20 to pass substantially directly downward into the leg 7. In the drum 15 distributing pipes 22, 22, 65 which open at one end into the vapor space 70 14 behind the dam 19, extend into the liquid space 18 near the bottom of the drum, and are provided with numerous openings for the admission of vapors into the liquid contained in the liquid space. The drum 15 is 75 provided with suitable manholes and liquid and pressure gages. A small pipe 23, provided with a check valve and located in the vapor space above the desired liquid level in the liquid compartment 18 of the drum, 80 opens into the vapor chamber 14 thru partition 17, and permits excess pressure in the vapor space in compartment 18 to be relieved into compartment 14.

85 Vapors evolved in the chamber 18 of drum 15 pass out thru a vapor pipe 24 into a drum 25 of construction similar to that of drum 15. The drum 25 is divided transversely into a vapor compartment 26 and a liquid compartment 27 by partition 28, the vapor 90 pipe 24 opening into the vapor chamber 26. A dam 29 in the vapor chamber 26 extends transversely of the drum between the opening of the vapor pipe 24 and the partition 28 and an overflow pipe 30 conducts the overflow of liquid from the chamber 27 down thru the vapor pipe 24 into the lower portion of the chamber 18 of drum 15. A vapor distributing pipe 32, which opens into the vapor space 26 back of the dam 29, extends 95 longitudinally into the liquid space 27 near its bottom. Vapors escaping from the drum 25 pass out thru the vapor line 31 to suitable condensers (not shown). It is readily apparent that the drum 5 and each of the 100 drums 15 and 25 may be lagged to prevent heat radiation, if desired.

105 In operating a still system of the character

above described, the still is charged with a suitable stock, say a gas oil (distillate) having a gravity of about 32° Baumé and a boiling point of, say, 450° F., and is first 5 heated under atmospheric pressure sufficiently to remove water vapor, etc. Pressure of say, 4 to 6 atmospheres, is then applied upon the system by any suitable means (not shown) controlling or connected to the 10 vapor line 31 and the still is fired until cracking distillation begins, from which time the firing is controlled to maintain such distillation. A suitable charge for a still of the type described is about 13,000 gallons. The 15 liquid compartment 18 of the drum 15 may have previously been filled with oil of the character of the charging stock or preferably a stock of somewhat lower boiling point, or alternatively, it may be filled during 20 the distillation operation by condensate from the vapors issuing from the drum 5. The liquid space in the drum or condenser 25 may be filled in either of these manners. The liquid in each of these drums becomes 25 heated by the passage of vapors therethru, which vapors are partially condensed, causing an overflow of liquid in the one case from the liquid compartment 27 of drum 25 into the liquid compartment 18 in drum 15, and 30 in the other from the liquid compartment 18 of the drum 15 into the drum or still 5. The liquids in these drums 15 and 25 are maintained at suitable temperatures to produce a distillate having the desired characteristics, 35 which in the case of a gasoline, will be about 650° F. for the liquid in the drum 15 and about 590° F. for the liquid in the drum 25. During the period in which distillation is effected in the still, a hydrocarbon oil which 40 may be of the same character as the stock charged into the still or may preferably be of a somewhat lower boiling point, and which is known as feed stock, is fed into the liquid chamber in the top drum where it 45 blends with the oil there present and results in an increased overflow of oil to the liquid space in the lower drum and conveyer into the still sufficient to maintain substantially a constant level in the still during distillation. If desired, shortly before the distillation period terminates, the flow of feed stock may be stopped and the level of oil 50 in the drum 15 permitted to become lower.

In operating a battery of stills, each of the 55 character of that above described, the control of the temperatures in the liquid chambers in the drums 15 and 25 may be effected and at the same time the stock utilized for charging the stills and for feeding thereto 60 during distillation may be preheated in the following manner:

Two mains or lines 33 and 34 are provided for the charging stock initially fed into the still, the former containing cold 65 charging stock and the latter hot. From

the cold charging stock lines 33, coils or loops 35 extend into the liquid chamber 18 in the drum 15, these being connected by a return pipe to the hot charging stock line 34. The coils 35 are preferably arranged in the 70 liquid compartment 18 slightly below the level of liquid therein, so that a thermocyclic circulation within the liquid itself may be established by the cooling effect of the charging stock flowing thru the coil. The cold 75 charging stock passes thru the coil 35 in each drum at a rate sufficient to maintain the proper temperature of the liquid in that drum, say 750 gallons per hour when the liquid content of the drum is about 6000 80 gallons. A suitable valve 36 may be provided to cut off or to decrease the flow of oil thru the coil 35 in case the liquid content of the drum is excessively cooled thereby. The cold charging stock lines 33 and the hot 85 charging stock lines 34 are connected by valved pipes 37 and 38 respectively, to the pipe 39 entering the still drum 5, thru which charging stock is admitted when the still is charged. If desired a suitable reservoir 90 (lagged, if desired) may be connected to the hot charging stock line 34 in order that the heated charging stock may accumulate for feeding into the stills.

Two mains or lines 40 and 41 are provided 95 for the feed stock, the former for the cold feed stock and the latter for the heated feed stock. Oil flows from the cold feed stock line 40 thru suitable coils 42 located in the liquid space of drum 25 in the same manner 100 as the coils 35 are located in the liquid space of drum 15, and the oil returns from said coil to the hot feed stock line 41. A valve 43 controls the flow of oil thru the coils 42. The feed stock lines 40 and 41 communicate thru 105 valved pipes 44 and 45 respectively with the pipe 46, thru which feed stock enters the liquid space in the drum 25. On consideration of Fig. 2 it will be noted that a coil is provided in each of the condenser drums 110 of a battery in the same manner as is more clearly illustrated in Fig. 1 for a single set of apparatus. The flow of oil thru the feed stock heating coil and the upper drum 25 is controlled to maintain the desired temperature, for example 590° F., in the liquid space of the still 25. 115

The pressure upon the various stills may be separately maintained, if desired. It is preferred, however, that it be controlled so 120 as to be uniform throughout the battery, for example, as illustrated in the prior patent to one of us, No. 1,129,034 of February 16, 1915.

Altho the present invention has been described in connection with specific details of 125 a method and apparatus for carrying out the same, it is not intended that these details shall be regarded as limitations upon the scope of the invention, except in so far as included in the following claims:

We claim:

1. The process of pressure oil distillation which consists in maintaining in a distilling system a body of oil under pressure and at a temperature suitable for effecting distillation thereof, passing the evolved vapors through a body of oil, thereby heating the oil and condensing a part of the vapors, refluxing the heated oil and condensate from the second body of oil, flowing a stream of oil in indirect heat conductive contact with said second body of oil, thereby heating the stream and cooling the body of oil, and feeding the heated oil from the stream into the second body of oil.

2. The process of pressure oil distillation which consists in maintaining in a distilling system a body of oil under pressure and at a temperature suitable for effecting distillation thereof, passing the evolved vapors through a body of oil, thereby heating the oil and condensing a part of the vapors, refluxing the heated oil and condensate from the second body of oil, flowing a stream of oil in indirect heat conductive contact with the second body of oil, thereby heating the stream and cooling the body of oil, controlling the flow of the stream of oil to maintain a determined temperature of the oil, and feeding the heated oil from the stream into the second body of oil.

3. The process of pressure oil distillation which consists in maintaining a plurality of bodies of oil under pressure and at a temperature suitable for effecting distillation thereof, passing the evolved vapors from said bodies of oil through corresponding separate bodies of oil, thereby heating the latter and condensing part of the vapors, passing streams of oil through the last mentioned bodies of oil in indirect heat conductive contact therewith, whereby the bodies of oil are cooled and the streams of oil are heated, collecting the heated oil from a plurality of such streams, and utilizing said heated oil as a charge for further distillation.

4. The process of pressure oil distillation which consists in maintaining a plurality of bodies of oil under pressure and at a temperature suitable for effecting distillation thereof, passing the evolved vapors from said bodies of oil through corresponding separate bodies of oil, thereby heating the latter and condensing part of the vapors, passing streams of oil through the last mentioned bodies of oil in indirect heat conductive contact therewith, whereby the bodies of oil are cooled and the streams of oil are heated, controlling the rate of flow of said streams to control the temperature of said bodies of oil, collecting the heated oil from a plurality of such streams, and utilizing said heated oil as a charge for further distillation.

5. The process of pressure oil distillation

which consists in maintaining a plurality of distilling bodies of oil under pressure and at a temperature suitable for effecting distillation thereof, passing the evolved vapors from said bodies of oil through corresponding separate bodies of oil, thereby heating the latter and condensing part of the vapors, passing streams of oil thru the last mentioned bodies of oil in indirect heat conductive contact therewith, whereby the bodies of oil are cooled and the streams of oil are heated, introducing oil from the heated streams into the said oil bodies and returning oil from the said oil bodies to the distilling bodies of oil.

6. The process of pressure oil distillation which consists in maintaining a plurality of distilling bodies of oil under pressure and at a temperature suitable for effecting distillation thereof, passing the evolved vapors from the distilling bodies of oil successively through separate bodies of oil, at successively lower temperatures, whereby said bodies of oil are heated and portions of the vapors are successively condensed, passing streams of oil in indirect heat conductive contact with those of the separate bodies of oil at higher temperatures, thereby heating the streams of oil, collecting the heated oil from these streams and utilizing it for distillation charge, passing other streams of oil in heat conductive contact with those of the separate bodies of oil at lower temperatures and feeding the heated oil from said streams into the distilling system.

7. The process of distillation which consists in subjecting a plurality of bodies of distillate oil of about 32° B. at 4 to 6 atmospheres pressure to a temperature suitable for the pyrogenetic distillation of gasoline therefrom, passing the vapors therefrom through bodies of oil, thereby heating the latter and condensing part of the vapors, flowing streams of like oil through coils in the last mentioned bodies of oil and controlling said streams to maintain the bodies of oil at about 650° F., collecting the oil from said streams and utilizing it as charging stock, passing the vapors from the last mentioned bodies of oil thru additional bodies of oil, thereby heating the latter and condensing a further portion of the vapors, flowing oil of lower specific gravity through coils in the last mentioned bodies of oil and controlling said streams to maintain said bodies of oil at about 590° F. and feeding the heated oil from said streams into the distilling system during distillation.

8. The process of treating hydrocarbon oils, comprising subjecting oil to a conversion temperature under pressure in a heating zone, passing the vapors evolved through a fractionating system wherein reflex condensate collects in a pool, the vapors passing through said pool, circulating fresh oil

80

through closed passages in contact with said pool of condensate, thereby preheating the fresh oil, and forcing preheated oil and condensate from the pool into the heating zone 5 to be subjected to conversion temperature under pressure.

9. In distilling apparatus, a heated still, a liquid reservoir communicating with the still and containing a body of liquid, means 10 for conducting evolved heated vapors from the still into the liquid in said reservoir, thereby heating the liquid, means for returning excess liquid from said reservoir to the still, a coil within the liquid body in 15 the reservoir, means for introducing liquid into the coil and means for withdrawing it therefrom, the liquid being thereby heated, and means for introducing the heated liquid from the coil into the still.
- 20 10. In distilling apparatus, a heated still, a liquid reservoir communicating with the still and containing a body of liquid, means for conducting evolved heated vapors from the still into the liquid in said reservoir, 25 thereby heating the liquid, means for returning excess liquid from said reservoir to the still, a coil within the liquid body in the reservoir, means for introducing liquid into the coil and means for withdrawing it th- re- 30 from, the liquid being heated, and conduits for introducing the heated liquid from the coil into the liquid body in the reservoir.

11. In distilling apparatus, a plurality of heated stills, liquid reservoirs communi- 35 cating with each of said stills, each reservoir containing a body of liquid, means for conducting vapors from the stills into the liquid bodies in the respective reservoirs, means for returning excess liquid from each of said 40 reservoirs to the respective stills, coils within

the liquid bodies in the reservoirs, conduits for introducing oil into said coils, conduits for withdrawing oil from said coils, mani- 45 folds for each of said sets of conduits, and means for introducing oil from each of said conduits into the still.

12. In distilling apparatus, a plurality of stills, a liquid reservoir communicating with each of said stills, the said reservoirs containing bodies of liquid, means for conduct- 50 ing vapors from the stills into said liquid bodies and means for conducting excess liquids from said liquid bodies into the stills, coils within the liquid bodies in the reservoirs, conduits for introducing liquid into 55 the coils, conduits for withdrawing liquid from the coils, manifolds for each set of conduits, conduits for introducing oil from each of said manifolds into the several stills, control valves for said conduits, secondary 60 liquid reservoirs communicating with each of the first-mentioned liquid reservoirs, a body of liquid in each of said reservoirs, means for conducting vapors from said first-mentioned liquid reservoirs into the liquid 65 bodies in the secondary liquid reservoirs, and means for conducting excess liquid from the secondary liquid reservoirs to the respective stills, coils in the liquid bodies in the secondary reservoirs, conduits for in- 70 troducing liquid into said coils, conduits for withdrawing liquid from said coils, mani- folds for each set of conduits, conduits for conducting liquid from each of said mani- 75 folds into the vapor systems of the stills and control valves for the last named conduits.
